UNITED STATES PATENT OFFICE

JACOB LUNDGREN, OF PHILADELPHIA, PENNSYLVANIA, ASSIGNOR OF ONE-HALF TO
THE CARLSON-WENSTROM MANUFACTURING COMPANY, INCORPORATED, OF PHIL-
ADELPHIA, PENNSYLVANIA, A CORPORATION OF DELAWARE.

BRAIDING-MACHINE.

1,189,591.

Specification of Letters Patent.

Patented July 4, 1916.

Application filed June 20, 1914. Serial No. 846,264.

To all whom it may concern:

Be it known that I, JACOB LUNDGREN, a citizen of the United States, residing at Philadelphia, in the county of Philadelphia and State of Pennsylvania, have invented 5 certain new and useful Improvements in Braiding-Machines, of which the following is a specification.

My invention relates to improvements in 10 braiding machines employing a set of spaced carriers adapted to carry a set of thread-supplying devices, a common carrier adapted to carry a second set of thread-supplying devices, means for supporting and rotating 15 said set of carriers and said common carrier in opposite directions to each other and for causing threads delivered from the said devices carried by the common carrier to move sinuously through the spaces between and 20 around the spaced carriers and the thread-supplying devices carried thereby and the threads delivered therefrom for the formation of the braid; and my invention relates 25 particularly to improvements in the type of machine shown and described in my Letters Patent No. 1,144,716, dated June 29, 1915, to which reference may be had.

The object of my present invention is the 30 simplification of the mechanism employed for guiding the threads delivered from the thread-supplying devices of the common carrier sinuously through the spaces between and around the spaced carriers and the thread-supplying devices carried thereby, as will be hereinafter fully described 35 and particularly claimed.

In the accompanying drawings, illustrating 40 my invention: Figure 1, is a side elevation of my improved braiding machine, parts of the thread guiding arms for the upper thread-supplying devices being broken away. Fig. 2, is a view of one of the upper thread-supplying devices and its carrier detached from the machine. Fig. 3, 45 is a development of a portion of the braid produced by my improved machine. Fig. 4, is a view, partly in section, of one of the thread guiding devices for the lower thread-supplying devices. Fig. 5, is a front elevation 50 of the machine, partly in section, on line 4-4 of Fig. 6. Fig. 6, is a horizontal section, on line 6-6 of Fig. 5. Fig. 7, is a horizontal section, on line 7-7 of Fig. 5. Fig. 8, is a vertical section of the lower por-

tion of the machine, on line 8-8 of Fig. 6. 55 Fig. 9, is a plan of the outer and inner members between which the endless sinuous course is formed and which support the sectional track.

Referring to the drawings, 2 designates 60 the base of the machine frame, 3 a central standard rising fixedly from the base and 20 three outer standards rising fixedly from the base and spaced around the central standard 3. Secured on the central stand- 65 ard 3 is a horizontal plate 18, and secured on the outer standards 20 is a horizontal plate 21, in the same horizontal plane with and surrounding the plate 18, but spaced therefrom and providing an endless, sinuous 70 course between the two plates 18 and 21, as clearly shown in Fig. 9.

Rotatable on the central standard 3 below the plate 18 is a carrier 8, carrying a set of thread-supplying devices 9 which are 75 mounted on suitable brackets 10 secured to the carrier 8. The carrier 8 is rotated by the main shaft 11 through co-acting bevel gear wheels 12 and 13 secured to the carrier 8 and shaft 11, respectively. The main 80 shaft 11 is mounted to turn in bearings 14 and 15 on the base 2; and the main shaft 11 is provided with a pulley 16 by means of which it may be driven.

Secured on the outer portion of the car- 85 rier 8 is a sectional, internal gear ring 29 which surrounds and coacts with the outer portions of small gear wheels 28 secured on the lower ends of a circular set of regularly spaced vertical shafts 27 extending up 90 through the plates 18 and 21 and rotatable therein. The upper ends of the shafts 27 have small gear wheels 26 secured thereto and the inner portions of the gear wheels 26 co-act with teeth formed on the outer 95 portions of a circular set of regularly spaced carriers 23, carrying a set of thread-supplying devices 24, corresponding in number with the devices of the set 9. The set of carriers 23 slide in and are supported and 100 guided by a sectional annular track 22 which is formed by the plates 18 and 21 and parts secured thereto and which is intersected by the sinuous course 35, as clearly shown in Fig. 9.

The threads from the lower thread-supplying devices 9 pass first through guide eyes 19 on the bottom of the carrier 8 and

- then up through vertical tubes 32 and from the tops of the tubes 32 to the braiding region A. Each tube 32 is carried by the free end of an arm 31 arranged between its 5 thread-supplying devices 9 and the carrier 8 and pivoted to the carrier 8, at 30, and arranged to move with its tube 32 toward and from the center of the machine, as the tube moves through a slot 33 in the carrier 8 10 through which the tube 32 extends, and also through the space between adjacent sections of the gear ring 29. The tubes 32 also extend up through the sinuous course 35 to a position near the same level with the tops 15 of the upper thread supplying devices 24. Each tube 32 is surrounded by an anti-friction roller 34 (see Fig. 4) adapted to cooperate with the walls of the sinuous course 35.
- 20 The thread from each upper thread-supplying device 24 passes around vertical pins 37 on its carrier 23, thence to and through guide openings in a vertical pin 38 on its carrier 23 and from the upper end of the pin 25 38 to the braiding region A.
- The braided material B passes from the braiding region A up through a guide tube 36 secured to an angle arm 39 which is vertically adjustable in a bracket 40 carried by 30 a pair of horizontal shafts 41 and 42 which extend between and are supported by side standards 43 and 44 fixed on the base 2, the bracket 40 being fixed to the shaft 41, the shaft 41 being fixed to the standards, and 35 the shaft 42 being rotatable in the standards. The braided material B passes up from the tube 36 to and around a grooved take-up wheel 45 mounted to turn loosely on the fixed shaft 41 between two fixed collars 40 thereon. The take-up wheel 45 has a gear wheel 46 formed thereon which co-acts with a pinion 47 secured on the rotatable shaft 42. Secured on the outer end of the shaft 42 is a gear wheel 48 co-acting with a gear wheel 45 49 on one end of a short shaft 50 mounted to rotate in a bearing 51 on the standard 44. The other end of the shaft 50 has a worm wheel 52 secured thereon which is driven by a worm 53 secured on the upper end of a 50 vertical shaft 54 which is mounted to turn in a bearing 55 on the standard 44. The lower end of the shaft 54 carries a bevel gear wheel 56 which co-acts with a similar wheel 57 on the main driving shaft 11.
- 55 The operation of the machine is as follows: Power is applied to the main shaft 11 to rotate it in the direction of the arrows in Figs. 1, 5 and 6 thereby rotating the carrier 8 in the direction of the arrows in Figs. 60 1 and 7 and rotating the take-up wheel 45, at a much slower speed, in the direction of the arrows in Figs. 1 and 5, by the gearing between the take-up wheel 45 and the main shaft 11. As the carrier 8 is thus rotated 65 in the direction of the arrows in Figs. 5 and

6, the gearing between the carrier 8 and the set of carriers 23 rotates the set of carriers around the track 22 at the same speed as the carrier 8 but in the opposite direction thereto. Thus the two sets of thread-supplying devices 9 and 24 are each bodily rotated in opposite directions to each other.

During the movement of the carrier 8, the arms 31 carried thereby move on their pivots 30 and the vertical tubes 32 are caused to 70 follow the sinuous course 35 by the rollers 34 engaging the walls thereof. This operation causes the tubes 32 to intersect the path of the upper thread-supplying devices 24 and to move toward and from the center of the machine from the outside to the inside and from the inside to the outside of said path. This operation also causes the tubes 32 to move between the adjacent sections of the gear ring 29 so that the tubes 32 may pass around the 80 outside of the shafts 27 supported by the plate 18 and around the inside of the shafts 27 supported by the plate 21, this being an important feature of my invention.

The gear wheels 26 are so related to the 90 teeth on the carriers 23 that before the teeth of a carrier 23 leave a gear wheel 26 they are engaged by the next adjacent gear wheel 26, so that the carriers are always maintained equally spaced from each other while being 95 driven.

The tubes 32 move around the machine with the devices 9 in the opposite direction to the devices 24, and the timing of the movement of each tube 32 with respect to the 100 movement of the devices 24 and their carriers 23 is such that each tube 32 will pass between the devices 24 and between their carriers 23, and around the outside and then around the inside of two adjacent devices 24 105 and their carriers 23 in alternate succession, and between each succeeding two adjacent devices 24 which were passed around by each tube's preceding tube, thus causing the tubes 32 to interweave the threads from the 110 devices 9 between and around the devices 24 and the threads delivered therefrom for the production of the braid illustrated in Fig. 3, in which each thread passes over and under two threads in alternate succession and 115 between the two threads over and under which the next adjacent thread passes. As rapidly as the braid B is formed, it is drawn up through the guiding tube 36 by the take-up wheel 45 which also draws the threads 120 from the thread-supplying devices 9 and 24, during the weaving of the braid.

I claim:

1. In a braiding machine, the combination of a supporting frame, two horizontal plates 125 supported on said frame and disposed in the same horizontal plane, one plate surrounding the other and the plates forming an endless sinuous course between them, a set of spaced carriers adapted to carry a set of 130

- thread-supplying devices, a sectional, annular track for supporting and guiding said carriers, said track being supported by said plates and intersected by said course, a rotatable carrier common to and adapted to carry a second set of thread-supplying devices, means for rotating said set of carriers and said rotatable carrier in opposite directions to each other, and a set of vertically-arranged thread-guiding tubes for said second set of devices, said tubes being movable on and carried by said rotatable carrier and extending through and guided by said sinuous course when the carrier is rotated.
- 5 2. In a braiding machine, the combination of a supporting frame, two members on said frame and forming an endless sinuous course between them, a set of spaced carriers adapted to carry a set of thread-supplying devices, a sectional, annular track for supporting and guiding said carriers, said track being intersected by said course, a rotatable carrier common to and adapted to carry a second set of thread-supplying devices, 10 means for rotating said set of carriers and said rotatable carrier in opposite directions to each other, said means including an annular set of shafts and gear wheels thereon, certain shafts of the set being supported by one of said members, certain shafts of the set being supported by the other of said members, and a set of thread guides for said second set of devices, said guides being movable on and carried by said rotatable carrier and extending into and guided by said sinuous course when the carrier is rotated.
- 15 3. In a braiding machine, the combination of a supporting frame, a central standard supported on said frame, an inner member supported by said standard, an outer member supported on said frame and surrounding the inner member and forming an endless sinuous course between them, a set of spaced carriers provided with gear teeth and adapted to carry a set of thread-supplying devices, said members being provided with means to support and guide said carriers in an annular path intersected by said sinuous course, and means for actuating said carriers and for guiding threads from a second set of thread-supplying devices through said course, said means including shafts rotatably mounted in said inner member, shafts rotatably mounted in said outer member, a gear wheel rotatable around said standard, 20 pinions on said shafts co-acting with said gear wheel, and pinions on said shafts co-acting with the gear teeth of said carriers.
- 25 4. In a braiding machine, the combination of a supporting frame, a central standard supported on said frame, an inner member supported by said standard, an outer member supported on said frame and surrounding the inner member and forming an endless sinuous course between them, a set of spaced carriers provided with gear teeth and adapted to carry a set of thread-supplying devices, said members being provided with means to support and guide said carriers in an annular path intersected by said sinuous course, and means for actuating said carriers and for guiding threads from a second set of thread-supplying devices through said course, said means including shafts rotatably mounted in said inner member, shafts rotatably mounted in said outer member, a gear wheel rotatable around said standard, 30 pinions on said shafts co-acting with said gear wheel, and pinions on said shafts co-acting with the gear teeth of said carriers.
- 35 5. In a braiding machine, the combination of a supporting frame, a central standard supported on said frame, an inner member supported by said standard, an outer member supported on said frame and surrounding the inner member and forming an endless sinuous course between them, a set of spaced carriers provided with gear teeth and adapted to carry a set of thread-supplying devices, said members being provided with
